(Cl. D54—13)

To all whom it may concern:

Be it known that I, William H. Brotherton, a citizen of the United States, residing at Rogersville, in the county of Hawkins and State of Tennessee, have invented a new, original, and ornamental Design for a Combination Fence Tool, of which the following is a specification, reference being had to the accompanying drawing, forming part thereof.

Figure 1 is a side elevational view of a combination fence tool, showing my new design,

Figure 2 is a rear elevational view,
Figure 3 is a front elevational view, and
Figure 4 is a top plan view thereof.

I claim:

The ornamental design for a combination fence tool, as shown.

WILLIAM H. BROTHERTON.
